AUTOMATIC WEATHER STRIP FOR DOORS AND THE LIKE

Filed June 27, 1927

FIG. 1

Patented Nov. 13, 1928.

1,691,315

UNITED STATES PATENT OFFICE.

LLOYD E. VAN AUKEN, OF LEMON GROVE, CALIFORNIA.

AUTOMATIC WEATHER STRIP FOR DOORS AND THE LIKE.

Application filed June 27, 1927. Serial No. 201 642.

My invention relates to automatic weather strips for doors and the like, and the objects of my invention are: first, to provide a device of this class which prevents all drafts under doors or windows; second, to provide a device of this class which is automatically operated, but does not interfere with the action of the door or window; third, to provide a device of this class which is carried in a recess portion under the door or window when not in use; fourth, to provide a device of this class which automatically swings down from a recess in the lower portion of the door and closes the space between the under surface of the door and the threshold; fifth, to provide a device of this class which permits a wide space between the door and threshold so that the door will not stick during wet weather, yet will close the space effectively; sixth, to provide a device of this class which does not operate until the door is almost closed, which at that point is tripped by a lever, thus causing the weather strip to extend downwardly on the outer side and adjacent to the threshold; seventh, to provide a device of this class which can be readily installed on the conventional door or casement window; and eighth, to provide a device of this class which is easy to apply, durable, efficient in its action, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a fragmentary elevational view of a door and door casing showing the door partially open and showing my device in relation therewith; Fig. 2 is an enlarged sectional view of my device through 2—2 of Fig. 3, showing by the solid line the door ajar and indicating by dotted lines the closed position thereof; and Fig. 3 is a sectional view through 3—3 of Fig. 2, with parts and portions in elevation to facilitate the illustration.

Similar characters of reference refer to similar parts and portions throughout the several views of the drawings.

The cover plate 1, weather strip support

plates 2 and 6, spacer 3, trip plunger 4, spring 5, weather strip 7, and plunger actuating means 8, constitute the principal parts and portions of my automatic weather strip device.

The door D is provided with a grooved portion D¹, which extends the whole length of the under edge thereof. The outer projection formed by the groove, that is, the one on the outer side of the door, is beveled outwardly. At the free end of the door and set flush therewith is a cover plate 1, of which the lower portion thereof covers the end of the grooved portion D¹ and the upper portion is secured to the door D by means of screws. The lower and outer sides 1^a and 1^b, respectively, of the cover plate 1 are flanged toward the pivoted end of the door and extend flush therewith. The outer, lower corner of the plate 1 and the adjoining flanged portions are cut away, forming a notched portion 1^c. A second plate 2, which serves as a support for the weather strip, extends upwardly from the extreme edge of the flange 1^a to the upper extremity of the grooved portion D¹ and is adjacent to the edge of the flange 1^b, thereby completely filling the end thereof. The outer projection formed by the groove D¹ is cut away so as to allow the plate 2 to meet the flanged portion 1^b. The cover plate 1 and weather strip support plate 2 are held apart by a spacer 3, which extends part way down from the upper extremity of the grooved portion D¹ and to which are secured both the plates 1 and 2. It will be noted that the plate 2 may be integral with the cover plate 1; also, the spacer 3 may be formed by punching out or flanging a portion of the cover plate 1 or weather strip support plate 2. Reciprocally mounted between the two plates 1 and 2, below the spacer 3, and resting on the flange 1^a is a trip plunger 4. At the inner lower side thereof is a notched portion 4^a within which rests one end of a spring 5, the other end of which rests against the inside projection of the door formed by the groove D¹. A lug 4^b is secured in one side of the trip plunger 4 which extends through a slot 2^a of the weather strip support plate 2.

At the pivoted end of the door is secured a second weather strip support plate 6, which is set slightly in the edge of the door and secured thereto above the grooved portion therein. Between the two weather strip supports 2 and 6 is pivotally mounted a weather

strip 7. The weather strip 7 is a flat strip, preferably metallic, with an enlarged upper side 7^a positioned near the upper inside corner of the groove D¹. From the end of the 5 enlarged side 7^a extend lugs 7^b, which extend through holes in the support plates 2 and 6. On the end of the weather strip adjacent the support plate 2 is a flanged portion 7^c, which extends downwardly parallel thereto. With- 10 in the flanged portion 7^c is a slot 7^d extending parallel with the surface of the weather strip 7. The lug 4^b of the trip plunger 4 extends through the slot 7^d and slides therein as the trip plunger moves back and forth, causing 15 the weather strip to rotate on its pivotal axis. The threshold used in connection with this device is the conventional threshold T with a weather baffle T¹. The trip plunger 4 engages the plunger actuating means 8, which 20 is a projection extending up from the threshold T adjacent to the doorjamb J, as shown best in Fig. 2 of the drawings.

The operation of the device is as follows:

When the door D is open, the weather strip 25 is held within the grooved portion D¹ by means of the spring 5, which presses the trip plunger 4 outwardly and which in turn engages the weather strip, as shown best by the 30 solid lines in Fig. 2 of the drawings. The weather strip remains in its concealed position until the door is brought to the position shown by the solid lines in Fig. 2 of the drawings. At this point the trip plunger 4 engages the projection 8 and causes the lug 35 4^b thereof to turn the weather strip on its pivotal axis as the door moves forwardly, thereby causing the weather strip to assume the position shown by the dotted lines in Fig. 2 of the drawings.

Though I have shown and described a particular construction, combination and arrangement of parts and portions, I do not wish to be limited to this particular construction, combination and arrangement, but desire to include in the scope of my invention, the construction, combination and arrangement substantially as set forth in the appended claims.

Having thus described my invention, what 50 I claim as new and desire to secure by Letters Patent is:

1. In a device of the class described, a door grooved at its lower edge, a weather strip supporting means secured over each end of said groove in said door, a plunger reciprocally mounted in one of said weather strip supporting means, a lug extending from said plunger through said weather strip supporting means, a weather strip pivotally mounted between said weather strip supporting means, and a slotted lug at one end of said weather strip shiftable and operatively connected with said lug in said plunger. 55

2. In a device of the class described, a door grooved at its lower edge, a weather strip supporting means secured over each end of said groove in said door, a longitudinally shiftable plunger reciprocally mounted in one of said weather strip supporting means, a lug extending from said plunger through 60 said weather strip supporting means, a weather strip pivotally mounted between said weather strip supporting means, a slotted lug at one end of said weather strip 65 operatively connected with said lug in said plunger, resilient means for holding said plunger in its extended position, thereby holding said weather strip in its non-functioning position, and a projection on the jamb of said door for forcing said plunger 70 to its inward position against the action of said resilient means. 75

3. In a device of the class described, a door grooved at its lower edge, a cover plate positioned over the free end of said door and over said groove, a second plate positioned within said groove and spaced apart from said cover plate, a plunger reciprocally mounted therein, a second plate secured to the pivoted end of said door over said groove, 85 a weather strip pivotally mounted in said first and second mentioned plates, a slotted lug at the one end of said weather strip, a projection on said plunger adapted to operatively engage said slotted lug, and a resilient means for holding said plunger in its extended position and indirectly holding said weather strip in its non-functioning position. 95

In testimony whereof, I have hereunto set my hand at San Diego, California, this 10th day of June, 1927.

LLOYD E. VAN AUKN.
